[57] ABSTRACT

A method and apparatus for preparing foundry moulds or cores wherein separate charges of sand and binder on the one hand and sand and catalyst on the other hand are supplied to a mixing chamber in which the separate charges are mechanically intermixed to produce a final sand/binder/catalyst mixture. The final mixture is then passed by gravity into a blowing chamber and the mixing chamber and the blowing chamber are moved apart to allow the final mixture to be blown from the blowing chamber into a mould or core box and further to allow the mixing chamber to be cleaned by suitable cleaning means.

FIG. 6.

FIG. 7.

**APPARATUS FOR PREPARING FOUNDRY MOLDS
OR CORES FROM COLD QUICK SETTING
SAND/BINDER/CATALYST MIXTURES**

This invention relates to a method and apparatus for preparing foundry moulds or cores from a quick cold setting sand/binder/catalyst mixture.

The invention provides a method of preparing a foundry mould or core comprising supplying separate charges of sand and binder on the one hand and sand and catalyst on the other hand to a mixing chamber in which the separate charges are mechanically intermixed to produce a final sand/binder/catalyst mixture, passing the final mixture by gravity into a blowing chamber and moving the mixing chamber and the blowing chamber apart to allow the final mixture to be blown from the blowing chamber into a mould or core box and to allow the mixing chamber to be cleaned by cleaning means.

Preferably, metered quantities of said charges are supplied to the mixing chamber whilst an outlet of the mixing chamber is closed, said charges being mixed in the mixing chamber for a predetermined time period and the outlet then being opened to discharge the final mixture.

The invention may be carried into effect either by movement of the mixing chamber to a position in which it is cleaned by said cleaning means, or alternatively by movement of the blowing chamber to a position in which the final mixture is blown from the blowing chamber into the mould or core box.

The invention further provides apparatus for preparing foundry moulds or cores comprising a mixing chamber, supply means for providing the mixing chamber with separate charges of sand and binder on the one hand and sand and catalyst on the other hand, a mechanical mixing element in the mixing chamber, an outlet from the mixing chamber for passing material by gravity from the mixing chamber into a blowing chamber, means for moving the mixing chamber and the blowing chamber apart to allow the final mixture to be discharged from the blowing chamber into a mould or core box and to allow the mixing chamber to be cleaned by cleaning means.

The mixing chamber may be movable between a first position in which it is adapted to deliver the mixed material to the blowing chamber, and a second position in which the mixing chamber is adapted to be cleaned by said cleaning means, or alternatively the blowing chamber may be movable between a first position in which it is adapted to receive the final mixture from the mixing chamber, and a second position in which the final mixture can be discharged into the mould or core box. Preferably, the purging means comprises compressed gases.

The invention will now be described, by way of example, with reference to the accompanying drawings in which:

FIG. 1 is a diagrammatic view of apparatus according to one embodiment of the invention, and

FIGS. 2 and 3 are diagrammatic view of modified forms of the apparatus shown in FIG. 1.

FIG. 4 is a diagrammatic view of apparatus according to another embodiment of the invention with the blowing chamber or core shooter in a first position and

FIG. 5 is a diagrammatic view of the apparatus shown in FIG. 4 with the core shooter in a second position.

FIG. 6 is a vertical section of a cylindrical mixing chamber showing the mixer.

FIG. 7 is a top view of FIG. 6.

In the arrangement shown in FIG. 1, a pair of screw-

5 type combined mixer conveyor units 1, for example units of the type described in our U.S. Patent Specification No. 1,051,651 are supplied with metered quantities of sand and resin (or any other binder) and sand and catalyst respectively and discharge their respective 10 mixtures into twin reservoirs 2. When material is required to prepare a mould or core, a first slide valve 3 controlling communication between the reservoirs and a mixing chamber 4 is opened admitting the separate mixtures to the mixing chamber.

15 The mixing chamber may be of the type disclosed in our co-pending Patent Application No. 8095/71 which has been cognated with our other co-pending Application No. 55725/71, i.e., of the type shown in FIGS. 6

20 and 7 comprising a vertical cylindrical wall 8, a base wall with an outlet 10 therein and a vertical axis rotary mixing element 12 in the chamber, the element comprising a pair of angle iron members 11 tangentially mounted to said axis and having rigid blades 16 attached thereto, or diametrically opposed spring steel

25 blades adapted to sweep the base wall and a further pair of spring steel blades 18 angularly offset from the first pair adapted to sweep the vertical wall. The second pair of blades 18 are fixedly attached to a cross member 20 which also serves to sweep the roof of the mixing

30 chamber. With this construction, if a mixing element, having diametrically opposed spring steel blades, is rotated at about 120 RPM, it has been found that the materials can be intermixed as they fall through the mixing 35 chamber in about three quarters of a revolution of the mixing element. Accordingly, the outlet from the mixing chamber, controlled by a second slide valve 5 is suitably angularly offset from the inlet. A conventional blowing chamber or core shooter 6 has an inlet 6a

40 controlled by a third slide valve 7, the inlet 6a being formed in a top plate 6b.

45 Preferably, a rotary mixing element having said pair of tangentially mounted angle iron members with rigid blades attached thereto, comprising the first pair of blades, is used, the mixing chamber being used as a batch mixer wherein metered amounts of the two separate mixers are introduced into the mixing chamber and intermixed for a predetermined period of time and then discharged.

50 During mixing, valve 7 can be open and valve 5 is closed. When sufficient material for a core or mould being prepared has been delivered to the mixing chamber, valve 3 is closed, and after mixing, the mixing chamber is slid across the top plate 6b, valve 5 is opened and when the mixing chamber outlet communicates with inlet 6a (as shown dotted) the final mixture is transferred by gravity into the core shooter. The core shooter valve 7 is then closed and the final mixture is shot from the core shooter into a core or mould box in the conventional manner. The mixer chamber is then returned to its initial position in which its still open outlet registers with an opening 6c in the top plate and the mixing chamber is connected to a source of compressed air which enters the chamber through tangentially disposed ports in the cylindrical wall to purge any material remaining in the chamber into a suitable receptacle.

55

60

65

After purging, valve 5 is again closed, valve 7 is opened and the apparatus is ready for the preparation of a further mould or core.

The apparatus shown in FIG. 2 is similar to that shown in FIG. 1 and like references are used to refer to like parts. The reservoirs 2 and valve 3 are eliminated and the separate mixtures are supplied to the mixing chamber by operation of the combined mixer conveyor units 1 for a period sufficient to provide the required amount of materials for a core or mould being prepared. In this case, after mixing, the final mixture is transferred directly by gravity into the core shooter by opening valves 5 and 7. Then these valves are closed, the mixture is shot, and the mixing chamber is moved to one side (shown dotted) for purging by opening of valve 5. After purging the mixing chamber is returned to its initial position for the next cycle.

The apparatus shown in FIG. 3 is similar in construction and operation to the apparatus shown in FIG. 2 except that the outlet slide valve 5 of the mixing chamber is eliminated and the materials received from units 1 are intermixed by the rotary mixing element as they are passed substantially straight through the mixing chamber and into the core shooter.

FIG. 4 shows apparatus according to another embodiment of the invention in a mixing and charging position and

FIG. 5 shows the apparatus in a position in which the core shooter or blowing chamber has been moved to a position for blowing the core or mould and for cleaning the mixing chamber.

In operation, separate mixtures of sand and binder on the one hand and sand and catalyst on the other hand are supplied from twin mixer conveyor type units 1 through a divided hopper 2 into a mixing chamber 4. Mechanical mixing means of the type as described above is operative in the mixing chamber, the duration of mix being dependent on the amount of ingredients present in the chamber and the chamber can be of the type disclosed in Application No. 8095/71 cognated with No. 55725/71. It has been found preferable that the duration of mix should be of the order of about 10 seconds. After mixing, the final mixture is transferred directly by gravity into the core shooter or blowing chamber 6 by opening valves 5 and 7. Valve 7 is then closed and the core shooter 6 is moved across to a position as shown in FIG. 5 for the shooting operation. The core or mould is shot by applying compressed air to the top and/or side of the core shooter and at the same time the mixing chamber 4 is purged with compressed gas into a suitable container. The core or mould is removed and valve 5 is closed ready for the chamber 4 to receive further ingredients for a fresh mix. The core shooter 6 is returned to its original position shown in FIG. 4 for the next cycle.

The core shooter or blowing head can be constructed to move on rollers running in tracks, slides or the like and driven by gears or pulleys from an electric motor. Alternatively, the driving force can be a pneumatic or hydraulic piston and cylinder assembly and the core shooter or blowing head can be mounted for pivotal movement through a gear quadrant or the like.

It is envisaged that the arrangements shown in FIGS. 1, 2, 3 and 4 can operate with mixing chamber constructions different to that described above and it is to be understood that the core shooters used with the equipment of the invention namely the supply means

and movable mixing chamber, are in each case of a quite conventional known type.

I claim:

1. Apparatus for preparing foundry moulds or cores from cold quick-setting sand/binder/catalyst mixtures comprising a mixing chamber, supply means for providing the mixing chamber with separate charges of sand and binder on the one hand and sand and catalyst on the other hand, a mechanical mixing element in the mixing chamber, an outlet from the mixing chamber for passing material by gravity from the mixing chamber into a blowing chamber, means for moving the mixing chamber and the blowing chamber apart to allow the final mixture to be discharged from the blowing chamber into a mould or core box and to allow the mixing chamber to be purged and purging means for the mixing chamber.
2. Apparatus according to claim 1 wherein the mixing chamber is movable between a first position in which it is adapted to deliver the mixed material to the blowing chamber, and a second position in which the mixing chamber is adapted to be purged by said purging means.
3. Apparatus according to claim 1 wherein the blowing chamber is movable between a first position in which it is adapted to receive the final mixture from the mixing chamber, and a second position in which the final mixture can be discharged into the mould or core box.
4. Apparatus according to claim 1 wherein said purging means comprises means for supplying gas to the chamber.
5. Apparatus according to claim 1 wherein the mixing chamber comprises a vertical cylindrical wall, a base wall with an outlet therein and a vertical axis rotary mixing element in the chamber, the element comprising a pair of angle iron members tangentially mounted to said axis and having rigid blades attached thereto adapted to sweep the base wall and a pair of spring steel blades angularly offset from said pair of angle iron members adapted to sweep the vertical wall.
6. Apparatus according to claim 5 wherein said second pair of blades are fixedly attached to a cross member which also serves to sweep a roof of the mixing chamber.
7. Apparatus according to claim 6 wherein the outlet of the mixing chamber is offset from an inlet of the mixing chamber through 270° in a direction of rotation of the rotary mixing element.
8. Apparatus according to claim 7 wherein the outlet of the mixing chamber is provided with a time controlled outlet valve adapted to close the outlet during a mixing operation and to open the outlet after a predetermined time interval for discharging the final mixture into the blowing chamber.
9. Apparatus according to claim 8 wherein metered amounts of said separate charges are intermixed in the mixing chamber in separate batches for a time interval of 10 seconds.
10. Apparatus according to claim 1 wherein the mixing chamber comprises a vertical cylindrical wall, a base wall with an outlet therein and a vertical axis rotary mixing element in the chamber, the outlet comprising a pair of angle iron members tangentially mounted to said axis and having rigid blades attached thereto adapted to sweep the base wall and a pair of

spring steel blades angularly offset from said pair of angle iron members adapted to sweep the vertical wall, the mixing chamber having an inlet, the outlet of the mixing chamber being offset from the inlet through 270° in a direction of rotation of the rotary mixing element and wherein the outlet of the mixing chamber is permanently open so that the material in the mixing chamber is intermixed by the rotary mixing element as said material is passed substantially straight through the mixing chamber and into the blowing chamber.

10

11. Apparatus according to claim 10 wherein the rotary mixing element is rotated at a speed of 120 RPM.

12. Apparatus according to claim 1 wherein the mixing chamber comprises a vertical cylindrical wall which is provided with tangentially disposed ports for connection to a source of said cleaning means to purge any material remaining in the mixing chamber, after discharge of the final mixture, into a suitable receptacle.
